SUPPORT AND DRAPE FOR CASKET
LOWERING DEVICES

Francis M. Compton, Waco, Tex.; Ida M. Compton, executrix of said Francis M. Compton, deceased

Application May 21, 1938, Serial No. 209,159

2 Claims. (Cl. 27—26)

This invention relates to cemetery equipment and has particular reference to catafalques such as those having spaced corner supports whereon are positioned lowering devices known as casket placers.

The principal object of the invention is to provide supporting posts for casket lowering devices of such nature that the lowering heads may be attached and detached therefrom with minimum time and effort and further, to eliminate the objectionable yielding action common to most types of supports when pressure is applied against the railing of the lowering device. This sometimes creates an embarrassing situation in ceremonies which is avoided by the use of the present invention.

Another object of the invention resides in the provision of a continuous curtain or drape for a catafalque whereby curtain edges, such as at the corners, present an even and uniform, and consequently a more pleasing appearance to the eye.

Another object of the invention is in the provision of a curtain for catafalques which is of such construction as to accommodate the variations in distances between the corner posts of placing devices.

A further object of the invention resides in the provision of attachments whereby the heading of the curtain is inclined toward the horizontal members of the placing device.

A still further object of the invention lies in the provision of coupling means between the placing device and the upright supporting corner posts.

Broadly, the invention seeks to provide a supporting post and a curtain for catafalques which latter presents a pleasing appearance by eliminating the curtain edges at the corners and by inclining the heading of the curtain toward the casket placing device.

With the foregoing objects as paramount, other and lesser objects will become manifest as the description proceeds taken in connection with the appended drawing wherein:

Figure 1 is a perspective view of the catafalque illustrating the continuous curtain or drape in place thereon.

Figure 2 is a fragmentary elevational view of the curtain particularly illustrating the attachment of the elastic cord employed at the corner posts.

Figure 3 is a fragmentary sectional view illustrating the attachment of the curtain heading to a horizontal shaft of the casket placing device.

Figure 4 is a perspective view of one of the corner posts illustrating the relative positions of clamps at the head thereof for engaging the casket placing device, and

Figure 5 is a fragmentary sectional view illustrating the adjustment set screws for operating one of the clamps illustrated in Figure 4.

Primarily the invention is comprised of a steel post such as illustrated in Figure 4, four of which are employed, one being stationed at each corner of the casket lowering device, the latter being of conventional construction. These posts each have flanges at their tops and bases.

The invention is further comprised of a continuous wall curtain 1, as illustrated in Figures 1 and 2, which is designed for vertical arrangement about the supports or posts 2 which are placed at the four corners of an open grave (not shown) for supporting a casket placing device 3. It is preferred that the curtain 1 be of velour, although any desired fabric may be used.

The conventional type placing devices are constructed with spherical corners 4, each being joined by horizontal members 5 forming an apparatus which is rectangular in shape. The spherical corners 4 are designed for resting upon the surfaces *a* of the posts 2 and are held in place by means inwardly projecting clamps 6, one of which is adjustable for the purpose of engaging and disengaging the said spherical member 4. This adjustability is accomplished by the provision of a longitudinal slot 7 within the lower portion of the clamp 6, as illustrated in Figure 5, and is retained in place by a set screw passing therethrough and threadedly engaging the under side of the surface *a* of the post 2.

It is apparent that the foregoing arrangement will prevent the entire structure from leaning when pressure is accidentally applied on one side or end and which is a source of annoyance to morticians when a ceremony is in progress. Moreover, by securing the spherical heads 4 to the supporting posts in the manner described, not only is a more rigid structure provided but the work of dismantling is made as easy as that of the usual structure which consists in simply placing the heads on the posts without means of securing.

The curtain 1 is secured to the spherical member 4 at its base and immediately above the supporting posts 2 by the tension of a continuous elastic cable 8 which is enclosed within a casing 9 and is attached to the curtain 1 by stitching 10. In the preferred form of construction the curtain 55

1 is gathered, as illustrated in Figures 1 and 2, and stitched to the casing 9, thus causing the gathers resulting from the contraction of the elastic 8 to be more uniform in their arrangement. By reason of this construction, that is, the gathering of the continuous curtain and the action of the elastic, the curtain can be adapted to placing devices of varied dimensions.

At determined intervals, the casing 9 is attached in depending arcs 11, as illustrated in Figure 2, to accommodate the contour of the spheres 4 at the corners of the placing device 3.

When the elastic cord is stretched in the manner previously described there will be a tendency 15 of the heading 12 above the arc 11 to be higher than at other points since the distance between the cord 8 and the outer edge b of the heading is greater than the distance between the cord 8 and the outer edge of the heading c disposed 20 between the corners; but since the sphere 4 causes the heading to be turned outwardly at the corners, the uniform height of the edge b is the same as that of the other edges c.

The heading c between the spheres 4 is made 25 uniform in appearance and is inclined inwardly toward the horizontal members 5 of the placing device 3 by attachment of hooks 13 therebetween, as illustrated particularly in Figure 3. The hooks 13 are attached to the under side of the heading 12 and the hooks 14 of which engage the horizontal member 5 thus insuring a uniform height 30 of the heading 12 and inclining the same inwardly.

Manifestly, the structure shown and described is capable of considerable changes and modifications by those skilled in the art and such changes and modifications which may be resorted to from time to time which may be considered within 5 the spirit and intent of the invention may also be considered as falling within the scope of the appended claims.

What is claimed is:

1. For association with a casket placing and 10 lowering device wherein the lowering device includes a plurality of rotatable shafts, a drape comprising a curtain vertically arranged there-around, a casing horizontally attached to said curtain and arcuated at spaced intervals on said 15 curtain, a continuous elastic cable within said casing and hook means attaching the heading of the said curtain to the said casket and lowering device.

2. For association with a casket placing and 20 lowering device wherein the lowering device includes a plurality of rotatable shafts, a drape comprising a curtain vertically arranged there-around, a casing horizontally attached to the said curtain and arcuately disposed at the corners of 25 said curtain, a continuous elastic cable within the said casing, means attaching the heading of the said curtain to the rotatable shafts of said device whereby to cause the upper portion of said drape to lie against a casket of said lowering device. 30

FRANCIS M. COMPTON.
